UNITED STATES PATENT OFFICE.

KARL Z. SHETLER, OF CLEVELAND, OHIO.

INTERNAL-COMBUSTION ENGINE.

1,106,522.

Specification of Letters Patent. Patented Aug. 11, 1914.

Application filed August 27, 1913. Serial No. 786,941.

To all whom it may concern:

Be it known that I, KARL Z. SHETLER, a citizen of the United States, resident of Cleveland, county of Cuyahoga, and State of Ohio, have invented a new and useful Improvement in Internal-Combustion Engines, of which the following is a specification, the principle of the invention being herein explained and the best mode in which I have 5 contemplated applying that principle, so as to distinguish it from other inventions.

My invention relates to internal combustion engines, and particularly that type thereof known as four cycle engines.

15 The object of the invention is to provide a four cycle internal combustion engine economical of manufacture and efficient in its operation.

20 The said invention consists of means hereinafter fully described and particularly set forth in the claims.

25 The annexed drawing and the following description set forth in detail certain means embodying my invention, the disclosed means, however, constituting but one of various mechanical forms in which the principle of the invention may be applied.

30 In said annexed drawing:—Figure 1 is a horizontal section of an engine embodying my invention and taken upon the plane indicated by line I—I in Fig. 3. Fig. 2 is a fragmentary vertical section taken upon the plane indicated by line II—II in Fig. 1. Fig. 3 is a front elevation, partly in vertical 35 section, the upper sectional portion being taken upon the plane indicated by line III—III in Fig. 1. Fig. 4 is a vertical transverse section taken upon the plane indicated by line IV—IV in Fig. 3. Figs. 5, 6, 7 and 8 40 are diagrammatic illustrations of the positions which the four valve-cranks occupy when the parts are in the positions illustrated in Figs. 1 to 4 inclusive.

45 The illustrated embodiment of my invention includes in its construction the four cylinders 1, 2, 3 and 4, each having the same bore and having their axes parallel to each other, as is usual. Each of these cylinders is provided with a piston 5 of the usual ordinary type. Each piston is connected with a 50 crank 6 articulating with the crank-shaft 7.

The two cranks at one end occupy the same angular position with reference to the axis of the crank-shaft and the other two cranks likewise occupy the same angular position, 55 but removed 180° from the positions of the first two named cranks, as shown in Fig. 3. One end of the crank-shaft is provided with a suitable fly-wheel 8 and the other end of said shaft has secured thereto a helical pinion 9 which meshes with a helical gear 10 having a diameter twice that of the pinion 9. The gear 10 is secured to the lower end of a vertical shaft 11 whose upper end extends into the gas tight housing 12 secured to the 60 upper left-hand end of the frame of the engine. To this upper end of said shaft is secured a helical pinion 13 which meshes with a helical gear 14 of same diameter fixed to a transversely located valve-actuating 65 crank-shaft 15. On each side of the gear 14 and on the crank-shaft 15 are two cranks 16 and articulating with each of these cranks is a connecting rod 17, as shown in Fig. 1.

Extending longitudinally along the upper 75 part of the frame and at the front of the machine, is a gas-supply duct 18, the right-hand end of which communicates with a suitable source of gas or fuel-supply. This duct is cylindrical and has its left-hand end suitably closed by means of a closure 19. Each cylinder is provided with an inlet-port 20 establishing communication between it and said duct and this communication is controlled by means of two sliding sleeve valves 80 21 and 22 respectively, the two left-hand inlet-ports being controlled by valve 21 and the two right-hand inlet-ports being controlled by valve 22. These valves are of hollow cylindrical form as shown in 85 Fig. 1. Valve 21 has formed upon its interior a lug 23 to which is secured a valve rod 24 articulating with one of the rods 17 at the front end of shaft 15. The valve 22 is likewise provided with a lug 23 to 90 which is connected a valve-rod 25 articulating with the other rod 17 on the front end of said shaft 15.

The two cranks 16 just referred to are set 90° apart as shown in Figs. 5 and 6, Fig. 100 5 being a diagrammatic representation of the position of the front crank and Fig. 6 a

similar illustration of the adjacent crank. As shown the axis of the duct 18 extends in a direction right angular with respect to the axes of the cylinders. Upon the opposite side of the frame and parallel with the duct 18 is an exhaust duct 26 similar in cross-section and diameter to the said duct 18. Located in this duct 26 are two exhaust valves 27 and 28 respectively, the right-hand end of said duct communicating with a suitable discharge and the left-hand end being closed by means of a suitable closure 29. These exhaust valves are connected with the other two cranks 16 as shown and these cranks occupy a position 90° apart, as shown in Figs. 7 and 8, Fig. 7 illustrating the position of the forwardmost of said two cranks and Fig. 8 the rearmost thereof. The first of said two cranks occupies a position 90° from the rearmost of the front two cranks 16, so that it will be seen that all of the cranks occupy positions 90° from each other in the direction of rotation of the crank-shaft 15. Each cylinder communicates with the duct 26 by means of an exhaust-port 30. The lengths of these valves is made such that the device will operate as follows: When the parts are in the position illustrated, as before mentioned, the valve-cranks 16 occupy the positions illustrated in Figs. 5 to 8 inclusive and the pistons of cylinders 1 and 2 are at the uppermost ends of their respective strokes and the pistons of cylinders 3 and 4 at the lowermost end of their respective strokes. The direction of rotation of the valve crank shaft 15 is that indicated by the arrow in Fig. 3 and by the arrows in Figs. 5 to 8 inclusive. In this described position of the parts, cylinder No. 1 will have just been exhausted of the gases of combustion, cylinder No. 2 will have therein the compressed charge, the piston in cylinder No. 3 will have just completed its operative stroke and will be ready to begin its exhausting action and the piston in cylinder No. 4 will have just completed its function of drawing in the next charge. Ignition now takes place in cylinder No. 2 and the continuation of the movement of the parts as a result thereof will cause the valves to move in the direction indicated respectively by the arrows shown thereon in Fig. 1. The movement of the pistons in the various cylinders to the opposite ends of their respective strokes, will cause cylinder No. 1 to be supplied with the uncompressed charge, the piston in cylinder No. 2 to effect its operative stroke, cylinder No. 3 to scavenge the products of combustion therein and the piston in cylinder No. 4 to compress its charge. This latter charge is therefore, at the end of this stroke, ready for ignition. Such ignition will cause the said piston in cylinder

No. 4 to then effect its operative stroke, cylinder No. 3 to receive its uncompressed charge, piston in cylinder No. 2 to scavenge its contents and piston in cylinder No. 1 to compress its charge. Ignition next takes place in cylinder No. 1, following which, after a complete cycle, ignition takes place in cylinder No. 3. Each piston therefore becomes operative in succession in the order named. In this manner I obtain a simple and effective four cylinder internal combustion engine of the four cycle type.

Having fully described my invention, what I claim and desire to secure by Letters Patent is:

1. In an internal combustion engine, the combination of four cylinders and suitable pistons therefor, each cylinder having an exhaust and an inlet-port communicating with one end of its bore; a fuel-supply duct communicating with all of said inlet-ports; an exhaust duct communicating with all of said exhaust-ports; two valves in each of said ducts, each controlling two ports communicating with the latter; and mechanism adapted to actuate said valves to effect a four cycle action of the engine.

2. In an internal combustion engine, the combination of four cylinders and suitable pistons therefor, each cylinder having an exhaust and an inlet-port communicating with one end of its bore; a fuel-supply duct communicating with all of said inlet-ports; an exhaust duct communicating with all of said exhaust-ports; two sliding valves in each of said ducts, each controlling two ports communicating with the latter; and mechanism adapted to actuate said valves so as to effect a four cycle action of the engine.

3. In an internal combustion engine, the combination of four cylinders and suitable pistons therefor, each cylinder having an exhaust and an inlet-port communicating with one end of its bore; a fuel-supply duct having its axis extending in a direction right angular with respect to the axis of said cylinders and communicating with all of said inlet-ports; an exhaust duct parallel with said supply duct and communicating with all of the exhaust-ports; two sliding valves in each of said ducts, each controlling two ports communicating with the latter; and mechanism adapted to actuate said valves to effect a four cycle action of the engine.

4. In an internal combustion engine, the combination of a plurality of cylinders and suitable pistons therefor; each cylinder having an exhaust and an inlet-port communicating with one end of its bore; a fuel-supply duct communicating with all of said inlet-ports; an exhaust duct communicating

with all of said exhaust-ports; a plurality of hollow sliding valves in each of said ducts controlling the ports communicating therewith; mechanism at one end of the engine adapted to actuate said valves to effect a four cycle action, and including valve rods connected with the interior of said valves, part of said rods extending through those

valves nearest to the aforementioned end of the engine.

Signed by me, this 25th day of July, 1918. ¹⁰
